UNITED STATES PATENT OFFICE.

WILLIAM NELSON PELOUZE, OF CHICAGO, ILLINOIS.

DESIGN FOR AN ELECTRIC FLAT-IRON.

43,508.

Specification for Design.

Patented Feb. 4, 1913.

Application filed November 13, 1912. Serial No. 731,184. Term of patent 14 years.

To all whom it may concern:

Be it known that I, WILLIAM NELSON PELOUZE, a citizen of the United States of America, and a resident of Chicago, in the county of Cook and State of Illinois, have invented a new, original, and ornamental Design for Electric Flat-Irons, of which the following is a specification, reference being had to the accompanying drawing, forming part thereof.

Figure 1 is a perspective view of the device in position for ironing. Fig. 2 is a perspective view of the iron standing on end.

I claim:

The ornamental design for an electric flat iron, as shown.

WILLIAM NELSON PELOUZE.

Witnesses:

EUGENE A. RUMMLER,
EDWIN PHELPS.
